UNITED STATES PATENT OFFICE.

GEORGI E. WASON, OF SAULT STE. MARIE, ONTARIO, CANADA, ASSIGNOR OF ONE-HALF TO PITE HAWRYLUK, OF SAULT STE. MARIE, ONTARIO, CANADA.

SWEEPING-MACHINE.

1,356,180.

Specification of Letters Patent. Patented Oct. 19, 1920.

Application filed July 22, 1919. Serial No. 312,483.

To all whom it may concern:

Be it known that I, GEORGI E. WASON, a citizen of Ukraine, residing at Sault Ste. Marie, in the Province of Ontario and Dominion of Canada, have invented certain new and useful Improvements in Sweeping-Machines, of which the following is a specification.

The primary object of the invention is to provide a sweeper adapted for hand operation in sweeping streets or sidewalks easily and quickly, the structure possessing great strength and being inexpensive to manufacture.

15 A further object of the invention is to provide a street sweeper for gathering up and transferring sweepings, provision being made for clearing the mouth of the receiving receptacle periodically thereby preventing any clogging and consequent scattering of the sweepings outside of the machine.

With these general objects in view my invention consists of the combination and arrangement of parts hereinafter described in connection with the accompanying drawings and in which like reference characters denote corresponding parts throughout the several views.

In the drawings, 30 Figure 1 is a side elevation of the invention with the cover member removed,

Fig. 2 is a top plan view thereof,

Fig. 3 is a front elevational view of the same,

35 Fig. 4 is a vertical transverse sectional view taken upon line IV—IV of Fig. 1 with the cover in position,

Fig. 5 is a vertical longitudinal sectional view of the lower portion of the invention,

40 Fig. 6 is a perspective view of a plate member employed showing a portion of the operating means, and

Fig. 7 is a top plan view of a side portion of the invention with the cover in position as shown in Fig. 4.

My invention broadly consists in a barrel-shaped receptacle 10 trunnioned at diametrically opposite points between ground wheels 11, rearwardly projecting handles 12 being provided after the manner of a push cart, a gear 13 carried by the axle 14 of one of the wheels 11 meshes with the gear 15 upon a brace rod 16 transversely journaled

between the handles 12 while a similar gear 17 upon a shaft 18 journaled between said handles 12 rearwardly of the rod 16 is in constant mesh with said gear 15.

A sweeping brush 19 has an axle 20 journaled in depending brackets 21 carried by the handles 12 while a gear 22 upon the axle 60 20 is in constant mesh with the gear 17. By grasping the curved rear ends 23 of the handles 12 the machine may be readily pushed forwardly or rearwardly with the brush 19 revolved by means of its gear connections with the aforesaid wheel 11 and the sweeping operation accomplished in this manner.

A removable lid 24 for the top of the receptacle 10 is adapted to fit thereover for normally closing the receptacle, a form of gear case or housing 25 being carried by said lid 24 for covering the outer sides of the gears 13, 15, 17 and 22, a flange portion 26 of the housing being adapted to rest upon the adjacent handle 12 as best illustrated in Fig. 7 of the drawings.

An entrance opening 27 in the rear side of the receptacle 10 adjacent the bottom 28 thereof is adapted for receiving sweepings therethrough from the brush 19 during the forward travel of the device. A pan 29 is hinged as at 30 to the bottom 28 of the receptacle 10 with its rear edge 31 in constant sliding contact with the road-bed 32 or other surface to be cleaned by the sweeping operation. It will be evident that the pan 29 will be automatically maintained in contact direct with the ground 32 during slight swinging movements of the receptacle 10 so as to insure the sweepings to enter the openings 27 at all times during the forward movement of the device.

A clearing plate 33 of arcuate form normally rests flatly upon the bottom 28 within the receptacle 10 with its curved rear edge 34 adjacent the entrance 27, a rod 35 being secured to the inner edge of said plate and trunnioned through opposite points in the receptacle 10. A T-shaped lever 36 upon one end of the rod 35 has its rearwardly projecting arm 37 pivoted to one end of a link 38 while the other end of said link is pivoted to a rocker arm 39 upon the adjacent side of the receptacle 10 adapted for operation by a cord 40 passing over pulleys 41

and 42 upon the adjacent handle 12 at the opposite side of the device from the gear case 25.

A pivoted operating lever 43 is connected 5 to the rear end of the cord 40 and to the adjacent handle 12 for convenience in grasping adjacent the hand hold portion 23 of said handle. During the forward movement of the sweeper, some of the sweepings from 10 the brush 19 passing through the opening 27 of the receptacle 10 will fall upon the plate 33 and the lever 43 is then depressed rearwardly swinging the plate 33 upwardly and forwardly for throwing the sweepings 15 farther into the receptacle 10 as illustrated in Fig. 5 of the drawings. A spring 44 connects the forward portion or arm of the T-lever 36 with an adjacent point upon the receptacle 10 for automatically returning the 20 plate 33 assisted by its own weight rearwardly to its normal position flatly resting upon the receptacle bottom 28. The complete operation of the invention has been substantially described it being seen that 25 the entrance opening 27 is kept free for the passage of sweepings therethrough by the manual actuation of the lever 43.

What I claim as new is:—

1. A sweeper comprising a wheeled receptacle having an entrance opening for sweepings, push handles attached to the receptacle, a rotary brush adapted for operation during the forward movement of the device, a clearing plate pivoted within the receptacle 30 adjacent the entrance opening, means operable adjacent the rear end of one of said handles operatively connected to said plate whereby the latter is moved upwardly and forwardly for carrying the sweepings inwardly of the receptacle and return means for said plate exteriorly of the receptacle. 35

2. In combination with a receptacle, wheels trunnioned at opposite sides thereof,

push handles attached adjacent opposite sides of the receptacle extending rearwardly 45 thereof, a brush journaled beneath said handles transversely of the device, the said receptacle having an entrance opening for sweepings at the rear side adjacent the bottom of the receptacle forwardly of the brush, a substantially semi-circular clearing plate journaled within the receptacle normally positioned flatly upon the bottom of the receptacle adjacent said opening adapted to receive sweepings thereon, a lever upon 50 one of said handles, and operative connections exteriorly of the receptacle between said plate and lever whereby upon the manual operation of the latter, the plate is adapted for inward swinging movement depositing the sweepings thereon forwardly 55 within the receptacle.

3. A sweeper comprising a wheeled receptacle having an entrance opening for sweepings, push handles attached to the receptacle, a rotary brush adapted for operation during the forward movement of the device, a normally horizontal plate pivotally mounted within the receptacle adjacent the entrance opening, and means for 60 moving said plate arranged exteriorly of said receptacle.

4. A sweeper comprising a wheeled receptacle having an entrance opening for sweepings, push handles attached to the receptacle, a rotary brush adapted for operation during the forward movement of the device, a pivotally mounted plate normally flatly lying upon the bottom of the receptacle with the swinging end thereof adjacent the outer 65 edge of the opening, and means for moving the plate upon its pivotal connection to deposit rearwardly thereof material swept 70 thereon.

In testimony whereof I affix my signature.
GEORGI E. WASON.
